SHARPENING DEVICE WITH ANGULAR AND
LONGITUDINAL ADJUSTMENTS

Blackwell K. Murchison, Brooklyn, N. Y.

Application July 21, 1951, Serial No. 237,888

6 Claims. (Cl. 76—86)

1

This invention relates to new and useful improvements in sharpening devices.

More particularly, the invention proposes a new sharpening device having a plurality of meshing sharpeners and guides and means for adjusting the angular and the relative longitudinal positions of said sharpeners and guides.

Heretofore sharpening devices have been constructed in which the meshing sharpeners and guides could be adjusted longitudinally relative to each other so that the points of contact between an article being sharpened and the sharpeners and guides could be varied and selected. However, the angles of the sharpeners and guides were fixed. An important object of this invention resides in so constructing the new sharpening devices that the angles, as well as the longitudinal distances of and between the sharpeners and guides may be varied at will.

More specifically, it is proposed to characterize the new sharpening devices by the provision of arcuate elements rotatively adjustably mounted on a pair of spaced members which themselves are adjustably mounted to move in a longitudinal line towards and away from each other. It is proposed to mount the plurality of meshing sharpeners and guides on these arcuate elements in order that the angles between the sharpeners and guides may be varied by adjusting the arcuate elements rotatively. The longitudinal positions of the sharpeners and guides may be varied by adjusting the spaced members longitudinally towards and away from each other.

Another important object of this invention resides in the construction of a sharpening device which includes a plurality of sharpening implements for cutting, grinding, honing and finishing knives and other articles, and in which the sharpening implements may be adjusted to various angular positions for convenience in engaging the edges or bevels of the knives and other articles against the sharpening implements. More particularly, it is contemplated to mount the sharpening implements upon a turnably mounted support which is mounted on a standard which may be rested on a table or other horizontal article or which may be attached to a wall or other object. It is proposed to associate a pawl and ratchet wheel with the turnably mounted support by which the sharpening implements may be held in various angular positions.

Another object of this invention resides in arranging the sharpening implements radially of the axis of turning of said support.

This invention also proposes to characterize 55 sectional view taken on the line 7—7 of Fig. 6.

2

each sharpening implement by a stud attached to one of a pair of spaced members upon which the arcuate elements previously referred to are mounted, and it is further proposed to pass said stud through the other of said members to control the spacing of the members, with a nut threadedly engaged on said stud.

Still further it is proposed to provide resilient means in the nature of a spring for normally urging said members apart.

Another object of this invention resides in the provision of clamp screws movably mounted in slots extending arcuate of the axis of turning of said arcuate elements for clamping the arcuate elements in rotative adjusted positions.

Still another object of this invention resides in the provision of means for removably supporting and clamping the sharpeners and guides on the arcuate elements.

Another object of this invention resides in constructing the arcuate elements with slots through which the stud referred to above passes, and to provide half round guides mounted on the stud and having half round guiding surfaces concentric with the axis of turning of said arcuate elements for turnably holding the arcuate elements. It is proposed to arrange resilient means between and abutting said half round guides for normally urging the spaced members supporting the arcuate elements apart.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawings forming a material part of this disclosure:

Fig. 1 is a side elevational view of a sharpening device constructed in accordance with this invention.

Fig. 2 is a plan view of Fig. 1.

Fig. 3 is an end elevational view of Fig. 1.

Fig. 4 is a vertical sectional view taken on the line 4—4 of Fig. 1.

Fig. 5 is a fragmentary horizontal sectional view taken on the line 5—5 of Fig. 1.

Fig. 6 is a fragmentary longitudinal sectional view taken on the line 6—6 of Fig. 2.

Fig. 7 is a fragmentary enlarged horizontal sectional view taken on the line 7—7 of Fig. 6.

Fig. 8 is a vertical sectional view taken on the line 8—8 of Fig. 1.

Fig. 9 is a fragmentary horizontal sectional view taken on the line 9—9 of Fig. 1.

Fig. 10 is an end elevational view similar to Fig. 3 but illustrating the device adjusted so that the sharpening implements are at different angular positions to those shown in Fig. 3.

The sharpening device, in accordance with this invention, includes a standard 12 mounted on a base 13 which may be rested on a table or other flat surface, or which may be attached to a wall or other support. A support 14 is turnably mounted on the standard 12 by a stud portion 15 which projects from one end of the support 14 and engages through an opening in the standard 12. A nut 16 threadedly engages on said stud portion 15 for connecting said support 14 and standard 12 together. A ratchet wheel 17 is connected coaxially on the support 14. Specifically, members 18 and 19 are attached to the support 14 with fastening elements 20, and said ratchet wheel 17 is secured to the members 18 and 19 with fastening elements 21. A pawl 22 is mounted on the standard 12 and is engageable with the ratchet wheel 17 for holding the support 14 in selected turned positions on the stud portion 15. This pawl 22 is pivotally supported intermediate of its ends by a pintle 23. A spring 24 is mounted about the pintle 23, see Fig. 6, and acts to urge the pawl 22 into locking position in which its front end engages the ratchet wheel 17. The rear end of the pawl 22 may be manually depressed to pivot the pawl 22 to disengage the ratchet wheel 17 which is then free to turn. Sharpening implements 25 and 26 are mounted on the support 14.

The sharpening implement 25 includes a pair of spaced members comprising said member 18 and a member 27. Means is associated with these members 18 and 27 by which they may be relatively adjusted in a longitudinal line towards and away from each other. This means includes a stud 28 which is fixedly attached to the member 18 by a fastening element 29. The stud 28 passes through an opening in the member 27 for slidably supporting the member 27. The member 27 is also provided with side flanges 30 which engage against the sides of the member 18 to assist in slidably connecting said members 18 and 27. A nut 32 threadedly engages on the outer end of the stud 28 for limiting sliding of the member 27. The member 27 is also provided with a fastening element 33 which abuts the stud 28 by which the member 27 may be fixedly attached to the stud 28 so that it is stationary in relation to the member 18 when desired.

An arcuate element 34 is rotatively adjustably mounted on each of the members 18 and 27, concentric with an axis located midway between the members 18 and 27 and at right angles to the longitudinal line of motion of the member 27 in relation to the member 18. Each arcuate element 34 is formed with a slot 35 through which the stud 28 passes.

Half round guides 36 are mounted on said stud 28 and are formed with outer half round guiding surfaces concentric with said axis of said arcuate elements 34 to engage and turnably hold said arcuate elements 34. An expansion spring 37 is coaxially mounted on the stud 28 and abuts the half round guides 36 for normally urging the guides 36 apart and in this way urging the arcuate elements 34 apart and against their arcuate seats on the members 18 and 27.

A plurality of meshing sharpeners and guides 38 are mounted on adjacent outer ends of the arcuate elements 34 and have adjacent working surfaces 39 which diverge outwards in a direction from the axis of the arcuate elements 34, see Fig. 6. These meshing sharpeners and guides 38 preferably are formed of tool steel such as Carboloy. The sharpeners and guides 38 in the design illustrated on the drawings comprise one sharpener or guide 40 mounted on one of the arcuate elements 34 and meshing with a pair of sharpeners and guides 41 mounted on the other of the arcuate elements 34, see Fig. 7. The sharpener and guide 40 is attached to the arcuate element 34 by a clamp piece 42 attached to the arcuate element 34 with a clamp screw and nut 43. The sharpeners and guides 41 are held spaced from each other by a separator portion 34' which is a part of arcuate element 34. The sharpeners and guides 41 are mounted on the arcuate element 34 with clamp pieces 44 which are held in position with a clamp screw and nut 45. The screws and nuts 43 and 45 may be loosened and then the sharpeners and guides 40 and 41 may be removed and replaced. The arcuate elements 34 are turnably adjustably mounted on the members 18 and 27 by clamp screws 46 movable in slots 47 which are concentric with said axis between said members 18 and 27. The clamp screws 46 are mounted on the arcuate elements 34 and engage through the slots 47 which are formed in the member 18 and 27 and are adapted to hold the arcuate elements 34 in selectively turned positions.

The sharpening implement 26 is identical in construction to the sharpening element 25, except for size. The sharpeners and guides 50 are larger and parts associated therewith are correspondingly larger. In this form of the invention said sharpeners and guides 50 are in the form of abrasive stones, natural or artificial. The implement 26 includes said member 19 and a member 51 spaced from said member 19. Associated with these members 19 and 51 is means for adjusting these members 19 and 51 in a longitudinal line towards and away from each other. This means includes a stud 52 fixedly attached to the member 19 with a fastening element 53. The stud 52 slidably supports the member 51. The outer end of the stud 52 is provided with a nut 54. A fastening element 55 mounted on the member 51 is engageable with the stud 52 for locking the member 51 in a fixed position when desired. The member 51 is provided with side flanges 56 which engage the sides of the member 19 for assisting in guiding the members 19 and 51 in the longitudinal line.

Arcuate elements 57 are rotatively adjustably mounted on each of the members 19 and 51. These arcuate elements 57 are concentric with an axis located midway between the members 19 and 51 and at right angles to the longitudinal line of motion of the member 51 in relation to the member 19. The sharpeners and guides 50 are mounted on the outer adjacent ends of the arcuate elements 57. These sharpeners and guides 50 are provided with adjacent working surfaces 58 which diverge in a direction outwards of said axis. The arcuate elements 57 are formed with slots 59 through which the stud 52 passes.

Half round guides 60 are mounted on the stud 52 and have half round guiding surfaces concentric with said axis to engage and turnably hold the arcuate elements 57. An expansion spring 61 is mounted on said stud 52 and acts against the half round guides 60 for urging the

guides 60 apart and in this way urging the arcuate elements 57 against the arcuate seats formed in the members 19 and 51. The arcuate elements 57 may be turnably adjusted and held in various rotative positions by studs and nuts 62 and arcuate slots 63. The studs and nuts 62 are mounted on the arcuate elements 57. The slots 63 are formed in the sides of the members 19 and 51. The sharpeners and guides 50 are releasably mounted on the arcuate elements 56 with clamp screws and nuts 63.

The operation and use of the device may be understood from the following:

The base 13 may be rested on a table or may be attached upon a wall. The angular positions of the sharpening implements 25 and 26 about stud portion 15 may be adjusted for one's convenience. To do this the nut 16 is given a slight turn so as to be loose. Then the pawl 22 is moved to disengage from the ratchet wheel 17. Now the support 14 may be turned to any angular position, as for example, the position shown in Fig. 10. The pawl 22 is released to re-engage the ratchet wheel 17 and the nut 16 is now tightened.

A knife or other article to be sharpened, conditioned, or finished is merely drawn through the working surfaces 39 or 58 of the sharpeners and guides. The angular positions of these working surfaces 39 and 58 may be varied for controlling the angle of sharpening of the knife or other object. The studs and nuts 46 and 62 may be loosened to loosen the arcuate elements 34 and 57 which now may be turned about their axis to positions in which the working surfaces 39 and 58 are as desired. Then the studs and nuts 49 and 62 are retightened to hold the arcuate elements 34 and 57 in their new positions.

The members 27 and 51 may be longitudinally adjusted towards and away from members 18 and 19, respectively, by turning the nuts 32 and 54, respectively. Adjustment of these nuts 32 and 54 force the members 27 and 51 towards the members 18 and 19 respectively when the nuts 32 and 54 are turned in one direction. The springs 37 and 61 are compressed during this adjustment. When the nuts 32 and 54 are turned in the other direction, the springs 37 and 61 move the members 27 and 51 away from the members 18 and 19, respectively. This longitudinal adjustment changes the points of crossing of the diverging working surfaces 39 and 58 of the sharpeners and guides 38 and 50, respectively. The members 27 and 51 may be locked in selected positions by tightening the fastening elements 33 and 55.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A sharpening implement, comprising a pair of spaced members, a stud attached to the first of said members and slidably passing through the second of said members so that the second of said members may move in a longitudinal line towards and away from the first member, a nut

threadedly engaged on said stud and selectively controlling the distance that said second member may move relative to the first member for providing relative unyielding spaced positions of said members, resilient means urging said second member away from the first member, arcuate elements rotatively adjustably mounted on said members concentric with axes located between said members and at right angles to said longitudinal line and having slots through which said stud passes, and a plurality of meshing sharpeners mounted on the adjacent outer ends of said arcuate elements and having adjacent working surfaces diverging in the direction outwards from said axes.

2. A sharpening implement, as defined in claim 1, in which said resilient means comprises a spring mounted on said stud and acting between said members.

3. A sharpening implement as defined in claim 1, in which clamp screws movable in slots arcuate of said axes act between said members and said elements for clamping said elements in rotative adjusted positions.

4. A sharpening implement as defined in claim 1, in which half round guides are mounted on said stud and having half round guiding surfaces concentric with said axes and engaging and turnably holding said arcuate elements, and said resilient means comprises a spring on said stud and abutting said half round guides.

5. A sharpening implement in accordance with claim 1, a standard, a support turnably mounted on said standard, said sharpening implement being mounted on said support, a toothed wheel connected coaxially on said support, and a pawl mounted on said standard and engageable with said toothed wheel for holding said support in selected turned positions relative to said standard.

6. A sharpening implement in accordance with claim 1, a second sharpening implement in accordance with claim 1, a standard, a support turnably mounted on said standard, said sharpening implements being mounted on said support on opposite sides thereof, a toothed wheel connected coaxially on said support, and a pawl mounted on said standard and engageable with said toothed wheel for holding said support in selected turned positions relative to said standard.
